(57) CLAIM

The ornamental design for a cigar box, as shown and described.

DESCRIPTION

FIG. 1 is a first perspective view of a cigar box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the cigar box thereof; and,

FIG. 10 is a perspective view of another state of the cigar box thereof.

The broken lines shown in the drawings depict portions of the cigar box that form no part of the claimed design.
